[57] **CLAIM**

The ornamental design for a foot massage roller, as shown and described.

DESCRIPTION

FIG. 1 is a top, front and left side perspective view of a foot massage roller showing my new design;
FIG. 2 is a bottom rear and right side perspective view thereof;

FIG. 3 is a front elevational view thereof;
FIG. 4 is a right side elevational thereto, the left side being identical thereof;

FIG. 5 is a cross-sectional view taken along lines 5—5 of FIG. 1;

FIG. 6 is a cross-sectional view taken along lines 6—6 of FIG. 1; and,

FIG. 7 is a right side elevational view thereof on a reduced scale, the broken line showing of the foot being for illustrative purposes only and forming no part of the claimed design.

*Fig. 3**Fig. 4**Fig. 5**Fig. 6**Fig. 7*
